UNITED STATES PATENT OFFICE

2,545,253

TYPEWRITER DESK

Maria Bergson, New York, N. Y.

Application April 1, 1948, Serial No. 18,379

3 Claims. (Cl. 312—26)

1

The present invention relates to typewriter desks, and more particularly to a new and improved typewriter desk which is adapted to be assembled with one or more interchangeable components in different ways to form different articles of office furniture, as desired.

In my copending application Serial No. 696,212, filed September 11, 1946, for "Office Furniture" there is disclosed novel sectional office furniture comprising a plurality of interchangeable components that are adapted to be assembled in different ways to form a wide variety of different articles of office furniture, as desired. This application is addressed specifically to a novel type-writer desk construction which may form a component of sectional office furniture of this type.

The principal object of the invention, accordingly, is to provide a new and improved type-writer desk construction which can be assembled with one or more interchangeable components to form an article of office furniture.

The aforementioned copending application discloses office furniture which comprises a main unit formed in the shape of a substantially flat table member having supports forming a knee-hole space and at least one other space adapted to receive a furniture component. Preferably the supports are vertical and are located between two opposite edges of the table member. The central space between the vertical supports forms a knee-hole and the outer spaces to the right and left, respectively, of the vertical supports are adapted to receive, selectively, a plurality of interchangeable furniture components by means of which the assembly may be converted to any one of a number of different articles of furniture.

The specific furniture component to which the present application is addressed comprises a typewriter desk having a space forming a knee-hole and including storage space for stationery, etc., if desired. The typewriter desk component is adapted to fit any one of the outer component receiving spaces under the table member, and can be pulled out in a manner similar to a drawer when needed.

Additional objects and advantages will be apparent from the following detailed description, taken in conjunction with the accompanying drawings, in which:

Fig. 1 is a view in perspective of a typewriter desk component constructed according to the invention and which is shown in partially assembled relation to a main unit:

Fig. 2 is a side view in perspective of the desk

2

shown in Fig. 1 with the typewriter desk component in the closed position;

Fig. 3 is a side view in perspective of the typewriter desk component shown in Figs. 1 and 2;

Fig. 4 is a top view in section, taken along line 4-4 of Fig. 5, looking in the direction of the arrows:

Fig. 5 is a side view in section taken along line 5-5 of Fig. 3, looking in the direction of the arrows; and

Fig. 6 is a partial view in section, showing a locking device for the desk illustrated in Figs. 3-5, inclusive.

3-3, inclusive.
Referring now to Fig. 1, the main unit of
15 an article of furniture constructed according to
the invention disclosed in my aforementioned co-
pending application is shown as comprising a
substantially flat, double top, rectangular table
member 10 having secured thereto a pair of
20 vertical supports 11 and 12 located between the
outer, narrow edges of the table portion 10.
The central space between the vertical supports
11 and 12 forms a kneehole to receive the knees
25 of the user and the outer spaces to the right
and left, respectively, of the vertical supports
11 and 12 are adapted to receive any one of
a plurality of different furniture components,
as desired, to form any one of a number of dif-
ferent articles of furniture. Central pigeonholes
30 13 are preferably provided on opposite sides in
the table member 10 of the main unit and a pair
of similar drawers 13a for pencils and the like
may be located near one narrow edge of the table
member 10, on opposite sides thereof, as shown.

35 One furniture component may comprise, for example, a box-like member 14, conforming in shape to one of the outer spaces beneath the table member 10 and having one or more drawers 15 slidably mounted therein. Preferably, the box-
40 like member 14 is mounted on rollers 16 to facilitate its movement from place to place, although these are not necessary. The desk drawer component 14 may include a single deep drawer or a plurality of shallow drawers. Fur-
45 ther, the desk drawer component 14 may be re-
tained in the assembled position by a hinged member 15a which is adapted to drag on the floor or floor covering when one of the drawers 15 is pulled out and which can be elevated when
50 it is desired to move the member 14.

55 Positioned in the space to the right of the vertical support 12 in Fig. 1 is a typewriter desk component 27 constructed according to the present invention. The typewriter desk component 56 27 is of such size that it can be readily received

in the space to the right of the vertical support 12, and it may be formed with a kneehole 28 (Fig. 3) and a plurality of horizontal or vertical pigeonholes 29 for stationery, envelopes and other necessary equipment.

The typewriter desk component 27 is provided with a typewriter table 30 carrying a typewriter 32 and secured to a liftable cover 31 at right angles to the table 30, as shown in Fig. 3. In the open position the cover 31 serves as a support for the work. As shown in greater detail in Figs. 4 and 5, the typewriter table 30 may be mounted on pivots 30a located on opposite sides of the desk component 27 and which are journaled in the sockets 30b on the typewriter table 30. The typewriter table 30 is hingedly connected to a flat member 31a which is pivotally mounted on the desk at 31b, longitudinal slot means 31d being provided to afford a slideable pivotal connection between the member 31a and the desk. The typewriter 32 may be counterweighted by a weight 31c secured to the flat member 31a.

The typewriter table 30 may be locked in the open position by a pin 33 (Fig. 6) which is urged by a compression spring 34 into a hole 35 in the side of the typewriter table 30. The spring 34 is seated in a recess 36 in a supporting member 40 secured to the desk in any suitable manner and engages a member 37 which carries the pin 33 and which is secured to a slide panel 38. By moving the slide panel 38 to the left, the pin 33 may be withdrawn from the hole 35 permitting the table 39 and the cover 31 to be moved to the closed position.

The typewriter desk component is of such size and shape that when in the position of non-use, shown in Fig. 2, the entire assembly conforms to the shape of a conventional type desk. When it is desired to use the typewriter, the typewriter desk component 27 is pulled outwardly, as shown in Fig. 1, until the desk cover 31 can be raised to permit use of the typewriter. Rollers 16 may be provided, as shown, to facilitate movement of the desk component 27.

From the foregoing, it will be understood that the invention provides a new and improved typewriter desk construction which is of great utility, particularly in business organizations having requirements for frequent changes in plant layout and plant equipment. By providing a typewriter desk component which may be assembled in either of several positions with respect to a main unit, an extremely flexible article of office furniture results.

It will be understood that the specific embodiment described above by way of illustration may be modified in a number of respects within the scope of the invention. The invention is not intended to be limited to the specific embodiment described and illustrated herein and the latter is susceptible of numerous changes in form and detail within the scope of the appended claims.

I claim:

1. In a desk for a typewriter and the like, the combination of an opening in the top of the desk, a member pivotally mounted in said opening, said member having a flat portion forming a cover adapted to be brought flush with the top of the desk to close the forward portion of said opening, and having another portion substantially at right angles to said first portion for carrying a typewriter or the like, a closure mem-

ber hingedly connected to said flat portion for closing the rear portion of said opening, a slideable pivotal connection between said closure member and the desk, means for applying a force to said closure member near said hinged connection substantially to counterbalance the weight of said typewriter, and means for locking said second member portion to the desk in the open position.

2. In a desk for a typewriter and the like, the combination of an opening in the top of the desk, a member pivotally mounted in said opening, said member having a flat portion forming a cover adapted to be brought flush with the top of the desk to close the forward portion of said opening, and having another portion substantially at right angles to said first portion for carrying a typewriter or the like, a closure member hingedly connected to said flat portion for closing the rear portion of said opening, a slideable pivotal connection between said closure member and the desk, means for applying a force to said closure member near said hinged connection substantially to counterbalance the weight of said typewriter, a spring-biased pin in the desk and adapted to enter a hole in said second member portion to lock said second member portion to the desk in the open position, and sliding means for moving said pin out of said hole to release said second member portion from the desk and to permit said member to be moved to the closed position.

3. In a desk for a typewriter and the like, the combination of an opening in the top of the desk, a member pivotally mounted in said opening, said member having a flat portion forming a cover adapted to be brought flush with the top of the desk to close the forward portion of said opening, and having another portion substantially at right angles to said first portion for carrying a typewriter or the like, a closure member hingedly connected to said flat portion for closing the rear portion of said opening, a slideable pivotal connection between said closure member and the desk, means for applying a force to said closure member near said hinged connection substantially to counterbalance the weight of said typewriter, a spring-biased pin in the desk and adapted to enter a hole in said second member portion to lock said second member portion to the desk in the open position, and sliding means for moving said pin out of said hole to release said second member portion from the desk and to permit said member to be moved to the closed position, roller means to facilitate movement of said desk, and releasable means rendering said desk normally difficultly movable.
